CREEP ELIMINATOR FOR STOCKINGS

Katherine Elsie Reid, Providence, R. I.

Application December 19, 1933, Serial No. 703,148

2 Claims. (Cl. 36—58.5)

My present invention relates to arrangements for increasing the life and wear of hosiery, and particularly by preventing creeping of the stockings during wear.

- 5 It has been found that the heels of thin stockings, and particularly chiffon stockings, will creep down under the foot when the shoe is worn, and that the resultant wrinkling of the stocking heel aggravates and increases the wear and tear produced by contact with the shoe edge. It is the 10 principal object of my invention to devise a creep eliminator that will prevent the creeping of the stocking heel and will thus reduce wear and tear of the stocking.
- 15 It has also been found that the creeping above mentioned increases the pull on the stocking threads, and thus further increases the tendency to wear and to stretch in the vicinity of the shoe edge. It is therefore an additional object of 20 my invention to reduce the thread pull, by maintaining the stocking heel in the initial position assumed when the stocking is put on.

With the above and other objects and advantageous features in view, as will hereinafter appear, my invention comprises an arrangement of parts more fully disclosed in the detailed description following, in conjunction with the accompanying drawing, and more specifically defined in the appended claims.

- 30 In the drawing, Fig. 1 is a perspective view of the novel creep eliminator; and

Fig. 2 is a fragmentary side view of a shoe with stocking and creep eliminator, parts being broken away to more clearly disclose the relative positioning.

Since the creeping of a stocking heel during walking and dancing, for example, creates wrinkles in the region of the back edge of the 40 shoe and results in pull on the upper portion of the stocking, I have provided a novel creep eliminator which is worn without discomfort and without attracting attention, and which locks the stocking heel in the position assumed when the 45 stocking is first put on.

My novel creep eliminator is designated 10 in the drawing, and includes a base section or tab 11 and an upstanding curved strap 12 adapted to fit the heel contour of the wearer as indicated in 50 Fig. 2. The strap is joined to the sides of the tab adjacent the front thereof, and may be integral with, or secured to the tab in any desired manner, as by stitching 13.

The tab and strap material may be of any suitable material capable of preventing creeping of the stocking, the preferred material being flexible and thin, as for example rubber impregnated textile material.

5 The creep eliminator has been found most effective when worn on the heel under the stocking, as indicated in Fig. 2; in this position the tab is pressed down on the stocking to prevent the stocking 14 creeping down in the shoe 15, and the back 16 of the strap is maintained adjacent to and aligned with the back edge 17 of the shoe so that no edge is presented below the shoe edge against which the up-and-down movement of the shoe on the foot might rub the stocking.

The novel creep eliminator is thus simple in construction, and effective in use, and serves to maintain the stocking heel between the strap and the tab in fixed position relative to the shoe 20 and to the remainder of the stocking, whereby creep of the heel, wrinkling at the back of the stocking, and increase in tension of the stocking threads, is prevented.

While I have described a specific structure for 25 obtaining the described results, it is obvious that desired changes in the size and arrangement of the parts, and in the material used, may be made to suit particular requirements, within the spirit and the scope of the invention as defined in the 30 appended claims.

I claim:

1. A creep eliminator for stockings, comprising a flat base portion adapted to be positioned beneath the heel of a wearer, and a strap portion 35 joined at its ends to the sides of the base portion intermediate the front and back thereof and curving upwardly and backwardly, whereby the back of the strap portion engages the upper portion of the heel when the flat base is positioned beneath 40 the heel.

2. A creep eliminator for stockings, comprising a flat base portion adapted to be positioned beneath the heel of a wearer, and a generally flat strap portion joined at its ends to the sides of 45 the base portion intermediate the front and back thereof and curving upwardly and backwardly, the interior surface of the strap portion being generally perpendicular to the plane of the flat base, whereby the backwardly extending part engages the upper portion of the heel when the flat base is positioned beneath the heel.

KATHERINE ELSIE REID.
